UNITED STATES PATENT OFFICE.

OSWALD F. JORDAN, OF ST. THOMAS, CANADA.

SPRING RAILWAY-FROG.

SPECIFICATION forming part of Letters Patent No. 501,946, dated July 25, 1893.

Application filed May 16, 1892. Serial No. 433,156. (No model.)

To all whom it may concern:

Be it known that I, OSWALD F. JORDAN, a subject of the Queen of Great Britain, residing at St. Thomas, county of Elgin, Province 5 of Ontario, Canada, have invented a certain new and useful Improvement in Spring Railway-Frogs; and I declare the following to be a full, clear, and exact description of the same, such as will enable others skilled in the art to 10 which it pertains to make and use the same, reference being had to the accompanying drawings, which form a part of this specification.

My invention relates to spring railway 15 frogs, and consists primarily in the employment of a hinged rail in combination with a closing spring and the main track, whereby many of the defects of the ordinary spring are entirely avoided, and also in the further 20 construction and combination of parts more fully hereinafter pointed out.

In the drawings, Figure 1 represents a frog with a single spring wing rail in combination with the main track for a single crossing. 25 Fig. 2 is a side elevation of the hinge thereof, which also answers as a side elevation of the hinge and strap. Fig. 3 represents a frog with two spring wing rails, in connection with the main track. Fig. 4 is a section through 30 the hinges, of Fig. 3, on line $x-x$. Fig. 5 is a section through line $y-y$ of Fig. 3. Fig. 6 represents a bottom view of the blocking used in the double spring wing frog, shown in Fig. 3 showing the peculiar form of construction 35 and the manner in which the rail flanges and the point are related thereto. Fig. 7 is a cross section on line $z-z$, Fig. 3; and Fig. 8 is a cross section on line $y'-y'$, of Fig. 1.

In the drawings, similar letters of reference 40 refer to similar parts.

A represents the main rails. A', the point.

B represents the wing rail. C, the base plate. D, the hinge. E, E', the blocking. F, the springs. G, G, stops.

45 d, d' , are the hinged straps respectively, which, as shown in Fig. 2, are bolted to the web of the rails, the hinge being so arranged that the strap attached to the main rail forms the upper knuckle of the hinge, while the 50 strap attached to the wing rail forms the lower knuckle.

B' is the bolt or pivot of the hinge, which

extends through the base plate, C, and is fastened by a nut d^2 at its upper end.

d^3 is a flange upon the upper strap, as shown 55 in the sectional Fig. 4.

The other parts will be named in the specific description.

In constructing this rail frog, the rails on the main track A, A, one of which runs to 60 the point A', and the other of which extends to the hinge, are solidly bolted or riveted through the flanges thereof to the base plate C, which is a heavy plate, of sufficient length and width to extend under and support the 65 whole of the frog. By this means of construction the whole system is rigidly connected together from end to end, so that no creeping motion or motion due to expansion or contraction can derange the working parts, as 70 is frequently the case with the ordinary spring frog.

In my construction, all of the expansion and contraction is taken up in the track on either side of the frog, while the frog itself 75 remains practically rigid and relatively immovable in all of its parts, except in the spring wing rail itself; and I know of no other form of construction which will permit of this result of obviating all danger of the cramping 80 of the parts, and of the remaining open of the wing rail in the manner I have stated.

Upon the outside of the wing and main rail, there are firmly attached by bolting the hinged straps d, d' . The inner ends of these 85 hinged straps are forged into a knuckle. These knuckles, as shown in Fig. 3, extend nearly to the outer edge of the base plate, the lower one of which rests thereon. The strap attached to the wing rail carries the under 90 knuckle which thus directly rests upon the plate. The strap upon the main rail has its knuckle resting on the knuckle of the strap on the wing rail. This form and arrangement of the knuckles are important, as the resistance of the wing rail to any displacing action is thereby much increased. Through the plate and both of the projections passes the bolt B', as shown in Figs. 2 and 4. The upper portion of the knuckle at d^4 is cut out, 95 the nut of the bolt thus resting in a recess of a depth equal to its thickness. The object of this is to guard the nut and the end of the bolt from accidental blows. The bolt passes

through the base plate, and thus keeps the knuckles and plate closely together at all times. Opposite the joint of the hinge, the main rail is cut at an angle sloping from the 5 outside backward on the inside, looking from the outer end of the wing rail. The end of the wing rail is fashioned to fit this joint tightly when the wing rail is snug up against the main rail. The outer side of the wing 10 rail carries a housing *f*, in which is inclosed a spiral spring, the outer end of this spring being engaged by a washer, and held by a bolt passing through the web of all of the contiguous rails out through a similar spring and 15 housing upon the opposite side. By screwing up the nut on the end of this bolt, both springs are drawn to an equal tension, and each spring is opposed to the other. This is not new, and needs no detailed description.

20 The wing rail is controlled and limited to its outward motion by means of a stop or stops, each of which consists in a *T*, the cross bar of which is firmly bolted or riveted through the web of the main rail. The web of the 25 wing rail is slotted to receive the arm of the *T*, it passing somewhat loosely through the slot, and being held at its outer end by the bolt *g*. Each of these slots is similarly constructed, and the description of one suffices 30 for all. It will be seen that the wing rail thus moves outwardly, and is limited in its motion by the bolt of the stop *G*. The stop also tends to prevent the wing rail from turning under the blows of the wheel flanges. It will be 35 noticed that the joint between the wing rail and the main rail is located at a point between the bends of the main rail and the frog point. This is important, as it shortens and saves lengths of both plate and blocking, enables 40 the wing rail to operate with greater certainty, with less liability to derangement, as the comparative shortness of the wing rail creates greater resistance to the overturning tendency of the flange of the wheels striking it in 45 passing.

The block *E* in Fig. 3 is peculiarly constructed. It extends from a point a little distance back along the main rail from the joint, as shown at *e*, and fills the space between the 50 webs of the rails at that point, as shown in the section through the hinge in Fig. 4. The upper surface of it is brought to a horizontal surface just under the width of the flange of the wheels, so that they will not touch the 55 block, while the wheel is rolling upon the rail. At the outer end of the block, there is an undercut upon each side, which permits the flanges of the rails to pass under the block. This undercut extends forward to 60 ward the point a short distance beyond the joint of the wing rail with the main rail, so as to permit the flange of the wing rail to also extend under the blocking. This extension of the flange of the wing rail under the blocking, in combination with the broad bearing 65 surface made by the hinge, makes an extremely strong construction, and make it very

difficult to detach the wing rail from its place through accidental blows, or any tendency to overturn it. Forward of this point, where the 70 blocking is cut out to receive the flange of the wing rail, the flanges of the wing rails are cut out, as shown at *e'*, and the block thenceforward rests with its full face, except as hereinafter stated, solidly upon the base plate. 75 and is firmly fastened thereto by rivets *e*², as shown in Figs. 3 and 6. The end of the block is split or opened to receive the point *A'* of the main rail, and at this point the flange of the main rail is retained and the block is also 80 undercut so as to permit this flange to have a bearing surface upon the base plate. This strengthens the point, and also tends to prevent it from turning or moving. The point is also preferably rigidly fastened in the block 85 by means of a bolt or rivet passing transversely through it and the two wings of a block, as shown in Fig. 3. As the block is of the same height throughout, it will be seen that it connects the main rails from a point beyond the 90 hinge or hinges with the main rail at the point *A'*, and even in case the wing rail or rails were entirely thrown out, the flanges of the wheel riding over the openings would be held up until the wheel had reached the main rail 95 beyond the opening thus left. This is an important point, because it is not an extremely unusual thing for the wing rail to be thrown out, either by means of hollow wheels or by some detached portion of the machinery falling 100 down and catching the outer end of the wing rail, breaking the connections and throwing it bodily out sidewise from the main track. In the case of ordinary spring rail frogs, when the wing rail is thus thrown out, a portion 105 of the main track is usually destroyed, and the wheels drop down upon the ties or between them in that portion, thus derailing the train. It will be seen that in my improved form, having a very short section of 110 rail, it could be thrown out in the manner specified, and the dropping of the wheel would be wholly prevented, and the train would pass over the track without even a perceptible jar.

Having thus described my invention, what 115 I claim is—

1. In a spring rail frog, the combination of a main rail, a point rail, a blocking transversely filling the space between the point rail and the wing rail and extending longitudinally between and connecting by appropriate means the main and point rails, substantially as described.

2. The combination of a spring actuated pivoted wing rail, a main rail, a point rail, a base plate connecting and supporting the whole, a blocking transversely filling the space between the wing and point rails, and extending longitudinally between and connecting the main and point rails, substantially as described.

3. The combination of a spring actuated pivoted wing rail, a main rail, a point rail, a base plate connecting and supporting the whole a blocking transversely filling the space be-

tween the wing rail, point and main rails, and longitudinally extending from the main rail to the point rail, and having its lower portion cut out, whereby the flange of the wing rail is held 5 and allowed to work underneath the blocking, and a laterally extended knuckle of the hinge on the opposite side of the wing rail, substantially as described.

4. In a spring frog for railways, in combination with the main rail and forming an extension thereof, a spring actuated wing rail pivoted to the main rail at a point between the bends of the main rail and the frog point, substantially as described.

5. The combination of a wing rail, a main rail, a point rail, and blocking transversely filling the space between the wing rail, point and main rails and notched to receive the point rail and having its lower portion cut out, whereby the flange of the point rail projects underneath the blocking, substantially as described. 15 20

In testimony whereof I sign this specification in the presence of two witnesses.

OSWALD F. JORDAN.
